OTHER PUBLICATIONS

Osram "Night Breaker" lamp marketed by Osram Sylvania Inc., on sale prior to present application filing date, product information appearing at website www.osram.com (1 page, in color).

Primary Examiner — Ian Simmons*Assistant Examiner* — Harold Blackwell, II*(74) Attorney, Agent, or Firm* — Edward S. Podszus**CLAIM**

The ornamental design for a lamp capsule with coating, as shown and described.

DESCRIPTION

FIG. 1 is a front perspective view of the ornamental design for the lamp capsule with coating;

FIG. 2 is a front view thereof;

FIG. 3 is a rear view thereof;

FIG. 4 is a side view, the opposite side being the same;

FIG. 5 is a top view; and,

FIG. 6 is a bottom view.

The broken lines in the drawings illustrate portions of the lamp capsule with coating which form no part of the claimed design.
